INVALID'S FOOTREST

Alexander H. Jones, Jackson, Miss.

Application March 16, 1951, Serial No. 215,878

3 Claims. (Cl. 155—169)

1

This invention relates to improvements in footrests, and more particularly to an adjustable supporting device for the legs and feet of an invalid which can be quickly and easily adjusted to any desired position for the comfort of the user.

A main object of the invention is to provide a novel and improved adjustable footrest which is simple in construction, which is adjustable over a wide range of different positions in accordance with the requirements of different individuals, and which is easy to manipulate.

A further object of the invention is to provide an improved adjustable invalid's footrest which involves inexpensive components, which is sturdy in construction, which is easy to operate, which may be employed to support either one or both legs of the person using the device, which is light in weight, and which is compact in size.

Further objects and advantages of the invention will become apparent from the following description and claims, and from the accompanying drawings, wherein:

Figure 1 is a top plan view of an improved invalid's footrest constructed in accordance with the present invention;

Figure 2 is a rear elevational view of the footrest shown in Figure 1;

Figure 3 is a cross-sectional view taken on line 3—3 of Figure 1;

Figure 4 is an enlarged cross-sectional detail view taken on line 4—4 of Figure 1;

Figure 5 is an enlarged cross-sectional detail view taken on line 5—5 of Figure 1;

Figure 6 is an enlarged cross-sectional detail view taken on line 6—6 of Figure 1;

Figure 7 is a cross-sectional detail view taken on line 7—7 of Figure 3;

Figure 8 is an enlarged cross-sectional detail view taken on line 8—8 of Figure 1.

Referring to the drawings, the device is designated generally at 11 and comprises a base 12 on which is supported the upstanding, threaded post member 13. As shown in Figures 2 and 3, the base 12 may comprise a central, vertical, internally threaded sleeve member 14 to which are secured a plurality of outwardly extending, inclined supporting legs 14', the ends of the legs 14' being curved downwardly and being provided with the upwardly flaring head portion 16 on by the base 12 may be readily moved on the floor. The post member 13 is threadedly engaged in the sleeve member 14, whereby said post member may be adjusted vertically with respect to the base 12.

The top end of the post member 13 is formed with the upwardly flaring head portion 16 on which is rigidly secured the horizontal plate mem-

ber 17. Plate member 17 is generally rectangular in shape and is firmly secured to the top of head portion 16 by a plurality of radial arms 18 extending from head 16 and riveted or bolted to the plate member 17, as shown in Figure 7. Extending through and rigidly secured to the head 16 is a horizontal shaft member 19 which is located below and which is transverse to the plate member 17, as shown in Figure 7. Designated respectively at 20, 20 are a pair of footrest pads which are slidably and rotatably connected to the respective portions of the shaft 19 on opposite sides of the plate member 17, as by spaced depending brackets 21 secured to the bottom surfaces of the footrest pads 20 through which the shaft 19 extends. The brackets 21 are arranged so that the pad elements 20 overlie the plate member 17 and are in sliding contact with the top surface of said member 17 when the foot pad elements are in inwardly adjusted positions.

Secured to the intermediate portion of the inside margin of each foot pad element 20 is an upstanding, semicircular plate member 22 provided with spaced apertures 23 located adjacent its periphery. Secured to each of the members 22 is an inwardly facing angle bar 24 formed at its intermediate portion with an upstanding semicircular plate element 25 provided with spaced apertures 26 arranged to selectively register with the apertures 23 in the member 22, whereby members 22 and 25 may be connected by a suitable fastening bolt 27, as shown in Figure 4. Secured to the bar 24 is an angle bar 28 arranged parallel to the base flange of bar 24 and defining a channeled guideway or track with respect to the base flange of the bar 24. With the foot pad elements 20 in horizontal positions, the bottoms of the bar elements 24 are flush with the bottom surfaces of the foot pad elements 20, whereby the foot pad elements and bar elements may slide on the top surface of the plate member 17. As above explained, the channel-shaped track elements defined between the bars 28 and the base flange portions of the bar 24 face inwardly and are in opposing relation. Designated at 29, 29 are respective lever members pivoted at 30, 30 to the plate member 17 and arranged for swinging movement in a horizontal plane parallel to the plate member 17. The ends of the lever members 29, 29 are provided with ball elements 31 which are slidably received in the channel-shaped tracks defined between bars 28 and the base flanges of the bar members 24. Designated at 32 is a shaft member which is disposed over the plate member 17 transverse to the shaft 19 and which is rotatably mounted at

one end in a bearing bracket 33 secured to the plate member 17. The shaft 32 has a threaded portion 34 on which is engaged a nut member 35 whose lower portion is slidably received in a notch 36 formed in plate member 17 and which extends parallel to the shaft 32. The nut member 35 is connected to the levers 29, 29 by respective link bars 31, 37, as shown in Figure 1, whereby the link bars 29, 29 are simultaneously rotated in opposite directions responsive to the rotation of the shaft 32. The inner marginal portions of the pad members 20, 20 are connected together by respective coil springs 38, 38 located adjacent the forward and rear margins of the pad members 20, 20 and secured in the end portions of the inwardly facing, channel-shaped tracks above described, as shown in Figure 5. The springs 38, 38 bias the pad members 20, 20 toward each other, but said pad members are maintained in separated positions by engagement of the ends of the levers 29, 29 in the opposing, inwardly facing guide tracks. From Figure 1 it will be noted that the ends of the lever members 29, 29 abut the guide tracks in the mid-portion of said tracks, namely, at locations substantially equally spaced from the biasing springs 38, 38, whereby the levers 29, 29 are effective to exert smooth, spreading force to urge the pad members 20, 20 apart against the biasing force of springs 38, 38 responsive to the rotation of the shaft 32. Said shaft is provided at its ends with a crank handle 39 for the manual rotation thereof.

It will be apparent from Figure 4 that when the pad members 20 have been disposed so that the members 22 have been moved just beyond the side edges of the plate member 17, the pad members 20 may be tilted to desired angular positions around the shaft 19 by unfastening the bolts 27. A pad member 20 may be secured in any desired angular position around the shaft 19 by securing member 22 to member 25 thereof by engaging a bolt 27 through a pair of registering apertures 23 and 26. It will be further apparent that the pad members 20 may be thus individually adjusted to desired angular positions to suit the requirements of an individual user of the device.

Designated at 40, 40 are respective extension members provided on the rear margins of the pad members 20, 20, each extension member comprising a rack bar 41 slidably supported in a channel bracket 42 secured to the under surface of a pad member 20 and provided at its outer end with an upstanding flange or abutment 43. Journalized beneath the rear marginal portion of each pad member 20 is a crankshaft 44 on which is secured a gear element 45 which meshes with a rack bar 41, as shown in Figure 8. Each crankshaft 44 is provided with a crank handle 45 located in the space between the pad members 20, 20, whereby the abutments 43, 43 may be extended to any desired positions by rotating the crank handles 45.

Designated at 47 is an auxiliary footrest element which comprises a base portion 48 and an upstanding flange 49. The auxiliary footrest element 47 is detachably secured to the forward marginal portions of the pad members 20, 20 by straps 50 connecting the forward corners of base 48 to the inside corner portions of the pad elements 20, 20 and by additional strap members 51 connecting the top corners of the flange 49 to the plate member 17, as shown in Figure 3. As shown in Figure 1, the auxiliary footrest element 47 is located in the space between the forward corner portions of the foot pad elements 20, 20 and may be thus employed as an auxiliary

foot support. However, if the use of said auxiliary element 47 is not required, said element may be removed by disconnecting the straps 50 and 51.

In using the device, the apparatus is adjusted to provide a desired spacing of the foot pad elements 20, 20 by rotating the hand crank 39. The auxiliary extensions 40, 40 may be adjusted to desired, rearwardly extending positions by rotating the hand cranks 45'. If it is desired to adjust the angular positions of the foot pad elements 20, 20, said foot pad elements are arranged in positions as shown in Figure 4, with the margins of the foot pad elements 20 located just beyond the side margins of the plate member 17, whereby the foot pad elements 20 may be unfastened and rotated around the shaft 19 to desired angular positions. As above explained, the foot pad elements 20 may then be secured in their desired positions of angular adjustment by engaging the bolt 27 through registering apertures 23 and 26 in the respective plate elements 22 and 25. It will be further apparent that the elevation of the foot pad elements 20, 20 may be adjusted by rotating the post element 13 in the sleeve 14.

While a specific embodiment of an improved invalid's footrest has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. An invalid's footrest comprising a base, an upstanding post member secured to said base, a horizontal shaft secured to the top portion of said post member, a horizontal plate member secured to said post member above said shaft, a pair of pad members slidably mounted on said shaft on opposite sides of said plate member and overlying said plate member, spring means connecting the pad members, a crankshaft journaled on said plate member and extending transversely of said first-named shaft, respective levers pivoted to the side portions of said plate member and each having one end portion thereof engageable with the inner side marginal portion of a respective pad member, a nut member threaded on the crankshaft, and respective links connecting the nut member to the other end portions of the respective levers, whereby rotation of said crankshaft moves the nut member therealong and causes the levers to rotate, thereby moving the pad members to vary the spacing therebetween.

2. An invalid's footrest comprising a base, an upstanding post member secured to said base, a horizontal shaft secured to the top portion of said post member, a horizontal plate member secured to said post member above said shaft, a pair of pad members slidably mounted on said shaft on opposite sides of said plate member and overlying said plate member, spring means connecting the pad members, a crankshaft journaled on said plate member and extending transversely of said first-named shaft, respective levers pivoted to the side portions of said plate member and each having one end portion thereof engageable with the inner side marginal portion of a respective pad member, a nut member threaded on the crankshaft, respective links connecting the nut member to the other end portions of the respective levers, whereby rotation of said crankshaft moves the nut member therealong and causes the levers to rotate, thereby

moving the pad member to vary the spacing therebetween, and respective rearwardly extensible auxiliary rest elements mounted on the rear marginal portions of the pad members.

3. An invalid's footrest comprising a base, an upstanding post member secured to said base, a horizontal shaft secured to the top portion of said post member, a horizontal plate member secured to said post member above said shaft, a pair of pad members slidably and rotatably mounted on said shaft on opposite sides of said plate member and overlying said plate member, spring means connecting the pad members, a crankshaft journaled on said plate member and extending transversely of said first-named shaft, respective levers pivoted to the side portions of said plate member and each having one end portion thereof engageable with the inner side marginal portion of a respective pad member, means on said inner side marginal portions defining channels slidably receiving the end portions of the levers, a nut member threaded on the crankshaft, respective links connecting the nut member to the other end portions of the respective

levers, whereby rotation of said crankshaft moves the nut member therealong and causes the levers to rotate, thereby moving the pad members to vary the spacing therebetween, respective rearwardly extensible auxiliary rest elements mounted on the rear marginal portions of the pad members, and a further, forwardly facing, auxiliary footrest element secured to the forward marginal portions of the plate member and said pad members.
